DESIGN FOR A GASOLINE GAUGE

Roy A. Johnson and Oscar F. Johnson,
Chicago, Ill.

Application June 28, 1941, Serial No. 101,785

Term of patent 7 years

To all whom it may concern:

Be it known that we, Roy A. Johnson and Oscar F. Johnson, citizens of the United States, residing at Chicago, in the county of Cook and State of Illinois, have jointly invented a new, original, and ornamental Design for a Gasoline Gauge, of which the following is a specification, reference being had to the accompanying drawing, forming part thereof.

Fig. 1 is a front elevational view; Fig. 2 is a side elevational view; Fig. 3 is a top plan view, and Fig. 4 is a bottom plan view of a gasoline gauge embodying our new design.

We claim:

The ornamental design for a gasoline gauge, substantially as shown.

ROY A. JOHNSON.
OSCAR F. JOHNSON.
